UNITED STATES PATENT OFFICE.

EUGEN ALBERT, OF MUNICH, GERMANY.

PROCESS FOR PRODUCING PRINTING-PLATES.

967,875.

Specification of Letters Patent. Patented Aug. 23, 1910.

Application filed December 4, 1908. Serial No. 466,005.

To all whom it may concern:

Be it known that I, EUGEN ALBERT, a subject of the Emperor of Germany, residing at Munich, in the Kingdom of Bavaria and Empire of Germany, have invented certain new and useful Improvements in a Process for Producing Printing-Plates, of which the following is a specification:

This invention relates to an improved process for the preparation of printing plates by etching.

The objects of the invention are to simplify the etching process, to render it less dependent upon the personal skill of the worker, and to economize time.

The copies required in the preparation of photo-mechanical printing blocks have heretofore been made almost exclusively by means of bichromate films; if the bichromate film is on copper, it is burned-in to form an enamel and itself constitutes the resistant etching film. As the high temperatures required for this process prejudicially affect metals other than copper, such for example as zinc, the film of bichromate (generally albumin bichromate) is only utilized indirectly as support for another etching ground, by coating it, after the copying, with an etching ground, generally by rolling-in an appropriate ink, whereupon the unexposed parts with the etching ground deposited thereon are developed with water and rubbing with cotton wool, and then, after drying, the covered parts of the plates are dusted with powdered resin and melted-on. This latter process does not give as good results as when the bichromate film itself is used as the etching ground, as the rolling-in of the ink, the manual development with cotton wool, the dusting with resin and the melting-on, impair the smoothness and fineness of the tone, especially in the case of delicate autotypes. Attempts have therefore been made to apply the etching ground to the subsequent printing surface in the first place, then to prepare this etching ground with a bichromate film, to copy and develop as usual, and then to utilize the bichromate film as a protecting film against the solvents for the etching ground. The process most nearly resembling this heretofore employed is described by Husnick as consisting of pouring over a metal plate a bitumen solution prepared in turpentine and benzine, or in some other etheric oil, and then treating the bichromate copy with a

mixture of two parts of olive oil and one part of turpentine oil, by rubbing the metal plate until the bared bitumen is washed off and the metal appears clean. The plate is 60 then washed with soap and water and it is endeavored to rub the bichromate coating away so carefully that the bitumen beneath it is not injured. The bitumen is sufficient for efficient first-etching, the plate is then 65 cleaned and prepared for the second etching in the usual chemi-graphic manner by rolling-in fresh ink and so on. To overcome the defects of that process and attain a satisfactory result, it is first of all necessary 70 to prevent the solvent from soaking through the bichromate film, which is of course very thin, as otherwise the etching ground would also be dissolved at places where it should be protected from the solvent by the bichromate skin. This condition can only be fulfilled by a solvent of considerable consistency or viscosity, so that it will not penetrate the unremoved portions of the bichromate skin before the etching ground has been dissolved 75 at the exposed places; etheric oils will not give this result as they are of low consistency. On the other hand the capacity of a mixture of turpentine oil and olive oil to act as a solvent is so small that the dissolving process must be assisted by rubbing with cotton wool, which manual operation requires personal skill and entails sources of error, like the bichromate-albumin process, the avoidance of which is the very object of 80 the process. It is also necessary that when the etching ground has been dissolved on the places not protected by the bichromate skin, it should be possible to wash the dissolving liquid or dissolving mixture from 85 the plate speedily and thoroughly, as of course, in spite of the consistency of the solvent, in the course of a considerable period of time the solvent would penetrate the remaining portions of bichromate skin. 90

The cleaning-off of the olive oil mixture with soap and water, which is advocated by Husnick for the purpose of cleansing the metal plates from the fats, is of course not well adapted to interrupt suddenly the dissolving process, if only for the reason that the soap does not exert its action immediately upon the fatty substances; apart from the interruption of the dissolving action, a short action of the soap and water does not even produce a thorough cleansing of the plate, while if the soap and water 100

105

110

is allowed to act for any length of time it readily penetrates the bichromate skin and attacks the bitumen beneath it, as is clearly apparent from Husnick's statement that 5 "the attempt must be made to rub the gelatin away by washing with soap and water so carefully that the bitumen beneath it is not injured."

The conditions essential for attaining a 10 successful result can only be obtained when bodies are selected for the etching ground which dissolve readily in consistent liquids readily miscible with water. Owing to their 15 resistance to acids, resins are most suitable bodies, as they readily dissolve in alcoholic liquids; for the greater parts these liquids mix readily with water in all proportions, and, for reasons of economy, water alone is 20 also used for removing the solvent from the plate as speedily as possible. Alcoholic liquids can also be very readily thickened with bodies which are soluble both in alcohol and in water, and which, such as tannic acid for example, even tend to harden the 25 bichromate skin; it is also possible to increase the dissolving power of the alcoholic dissolving liquid by adding small quantities of acids or bases, on the one hand by the formation of the so-called esters and on the 30 other hand, by the formation of resinates. Alcohol also mixes in all proportions with glycerin, which is the most consistent liquid in existence, and which again is soluble in water in all proportions; if etheric oils be 35 selected, all these favorable factors are excluded completely.

Broadly this invention consists in using 40 alcoholic solutions of considerable consistency and high solvent capacity so that the etching ground readily dissolves if they are merely poured over the plate, or if it be immersed therein, before the solvent has filtered through the unremoved portions of the bichromate skin, and in quickly interrupting 45 the dissolving process by bringing the plate at the proper moment beneath a water pipe, preferably provided with a distributing rose.

For a more exact exposition of the invention 50 a drawing is made a part of this specification and in it there is graphically represented sections of a plate indicating different stages in its preparation.

Figure 1 represents the plate with first 55 coating applied; Fig. 2 represents it with the second coating applied to the first coating; Fig. 3 shows the prepared plate with portion of the second coating removed; and Fig. 4 shows it with corresponding portions 60 of the first coating removed.

The particular steps of the process and the materials preferred are as follows:— First, the base plate Z is covered with resin to form an etching ground E, next a bichromate film B is deposited over the whole, 65

and the copy formed by exposing to light the plate thus prepared and then dissolving in water the soluble portions of the gelatin or bichromate film from between the dots, leaving the insoluble portions or dots as in Fig. 3; the plate is then immersed in a liquid consisting of alcohol which has been thickened by the addition of tannic acid or glycerin, or both, to strengthen its dissolving power. This readily dissolves the exposed parts of the resin from the plate Z, Fig. 4, the other parts being protected by the bichromate film, and as soon as that is accomplished the dissolving process is instantaneously stopped and the plate cleansed by bringing it at the proper moment beneath a water pipe provided with a distributing spray, the plate being then ready for the etching bath. By this means it is possible to make an impression from the plate 85 after the preliminary etching, to free the plate from the residue of ink adhering to it by means of benzin or turpentine and drying it with sawdust, and then for the retouching process to be carried out and the 90 final etching undergone without rolling-in fresh ink, dusting with resin powder, and subjecting to heat as has been necessary in processes employed hitherto which frequently gave rise to error and loss of time. 95

Besides economizing time the results are more certain since the positive printing elements are still covered with the original etching film when the plate is operated on by the retoucher who is therefore certain 100 that the desired effects will be obtained in the final etching. These advantages apply equally when the plate, instead of being etched, is gummed and treated as a lithographic plate. 105

An important advantage obtained by using 110 alcoholic substances for the etching ground is found in the fact that there are a number of alcoholic resins to choose from which do not dissolve in etheric oils. For instance sandarac is insoluble in benzin, or turpentine.

A plate on cheap metal can be obtained by this process giving results equal in quality 115 to those of a copper plate.

What I claim as my invention and desire to secure by Letters Patent is:—

1. The herein described process of treating printing plates, which consists in covering the plate with an etching ground which 120 is insoluble in the substance used for cleansing the plate after preliminary etching, overlaying the etching ground with a sensitized film, then photographically transferring the copy thereto and washing away the unaffected portions of the film with water, dissolving the etching ground where not covered by the copy by means of a liquid of considerable consistency or viscosity, and quickly interrupting the dissolving process 125 130 135

when complete by removing the solvent with a liquid which will not dissolve the etching ground, substantially as and for the purpose set forth.

5. 2. The herein described process of treating printing plates, which consists in covering the plate with an etching ground of a resinous substance, coating this with a bichromate film, photographically transferring the 10 copy thereto and washing with water, and then subjecting the plate to the action of an alcoholic liquid readily miscible with water, substantially as and for the purpose set forth.
15. 3. The herein described process of producing printing plates, which consists in covering the plate with an etching ground of a

resinous substance, coating this with a bichromate film, photographically transferring the copy thereto and washing with water 20 to remove the soluble film, then subjecting the plate to the action of a solution of alcohol to which have been added glycerin and tannic acid, quickly stopping the dissolving process when complete by holding the plate beneath a water spray, and finally etching the plate thus prepared, substantially as described herein.

In testimony whereof I affix my signature in presence of two witnesses.

EUGEN ALBERT.
